UNITED STATES PATENT OFFICE.

JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

OVERSEAMING-MACHINE.

1,217,977.

Specification of Letters Patent.

Patented Mar. 6, 1917.

Application filed June 21, 1915. Serial No. 35,389.

To all whom it may concern:

Be it known that I, JOSEPH M. MERROW, a citizen of the United States, residing in the city of Hartford, county of Hartford, State of Connecticut, have invented certain new and useful Improvements in Overseaming-Machines; and I do declare the following to be a full, clear, and exact description of the same, reference being had to the accompanying drawings, forming a part of this specification, and to the figures and numerals of reference thereon.

This invention relates to overseaming machines of that type wherein a reciprocating needle coöperates with a looper or loopers in a manner to produce overedge stitches. Stitches of this general character form the basis of a great variety of fabric edge finish and the rapidity with which a finish may be produced is in many cases of the uttermost importance. In order that mechanisms for producing these finishes may attain and withstand the extremely high speeds so desirable, simplicity of construction in a marked degree is quite essential. With this fact in mind the present invention has been conceived and developed, the primary object thereof being the provision of a simplified construction for looper mechanism employed in producing overedge stitches, special attention having been given to the support of moving parts to insure smoothness of action throughout continuous operation thereof at high speeds.

In a pending application filed December 12, 1914, Serial Number 876,917 there is shown and described a form of looper mechanism adapted for sewing machines of the Merrow type. One of the loopers in the mechanism mentioned is pivotally mounted on a slide, whereby in addition to an oscillatory movement, said looper may be moved bodily in a right line. In contradistinction to this action the corresponding looper of the present invention is mounted for oscillatory movement upon a pivoted support whereby it may be reciprocated in a curved path instead of in a rectilinear one.

In the drawings accompanying and forming a part of the present specification there is shown in detail one convenient form of embodiment of the invention, it is, however, to be understood, that the improvement set forth is not limited to the embodiment herein shown as it is in many respects susceptible

of variation without departure from the scope of the invention as defined by the appended claims.

Referring to the drawings:

Figure 1 is a front elevation of a Merrow sewing machine with certain parts broken away to better show the embodiment therein of mechanism comprising the present invention.

Fig. 2 is a view of the inner face of a frame cap showing looper mechanism mounted thereon, and:

Fig. 3 is an edge view of the frame cap and a part of the looper mechanism shown in Fig. 2, there being also shown in this figure parts of each of a pair of cam cylinders.

Like characters of reference designate similar parts throughout the several views of the drawings.

The numeral 1 designates an eye pointed needle which may be either oscillated or reciprocated to penetrate fabric as the latter is fed by suitable mechanism (not shown) between the needle plate 2 and presserfoot 3 to receive stitches composed of one or more threads enchain by looper mechanism and secured into said fabric at the needle penetrations. As shown the needle 1 is mounted for oscillatory movement in the needle carrier 4 which is pivotally supported on the machine frame to permit of its being actuated in the customary manner that will soon be made apparent.

Within the machine frame 5, are a pair of cam cylinders 6 and 7, secured respectively to shafts 8 and 9. To the shaft 8 is secured the combined driving pulley and hand wheel 10. Intermeshing gears 11 and 12 are secured respectively to cam cylinders 6 and 7, whereby rotation of driving shaft 8 will cause the cam cylinders to rotate in unison to effect, as will hereinafter appear, the operation of looper mechanism supported on the inner face of a removable frame cap 13. Needle carrier 4, above mentioned, is connected by a link 14 with an eccentric extension of the shaft 9 whereby when the latter rotates said carrier will be oscillated about its supporting pivot.

The looper mechanism as illustrated in the drawings includes a pair of co-active loopers each of which is also co-active with the fabric penetrating needle. One of the loopers is shown with a thread car-

rying eye while the other is shown with simply a thread engaging notch or throat. It will be understood that the form of the loopers in the respect just noted may be 5 changed to fulfil different requirements as to the character of stitch to be produced.

- One of the loopers, as 15, may be considered as including a pivoted carrier as 16, supported on the inner face of frame cap 10 13 by the pivot or stud 17. Projecting from looper 15, intermediate its free end and the pivot 17 is a stud 18 provided with an anti-friction roller 19 adapted to engage a cam groove 20 in the juxtaposed cam cylinder 6. 15 Referring now to the other looper, designated by 21, it, together with its carrier 22, may be described as cruciform. The oppositely disposed arms extending from the central portion or mid arm 23 of said carrier are provided with studs 24 and 25 supporting respectively anti-friction rolls 26 and 27, adapted respectively to engage correlated grooves 28 and 29 in the respective cam cylinders 6 and 7. Pivoted at one end to 20 an arm of carrier 22 in alinement with one of the studs 24 or 25, preferably the latter (as shown) is an arm 30 pivoted at its opposite end for swinging or oscillatory movement about a stud 31 secured in the frame cap 13. 25 The several cam grooves mentioned are formed with definite relation therebetween and the cams and needle reciprocating means are intergeared and connected to operate in synchronism whereby the stitch 30 forming elements will be caused to traverse their respective paths in proper timing to render co-action between the loopers and also between each of them and the needle. 35 The looper 15 oscillates about its stationary pivot in a path below the plane of the needle plate 2, said path intersecting the path traversed by the needle, while the looper 21 is oscillated about a movable pivot so that it traverses a path which intersects 40 both the path of the other looper and the path of the needle, the points of intersection being respectively below the plane of the needle plate at one side thereof and above the needle plate. 45 Ample support is provided for looper 15 by the stud 17, the looper 21, however, and the oscillatory arm to which it is pivoted preferably have associated therewith means to furnish additional support to that afforded by the stud 31. I provide novel 50 means for effecting this supplemental support and as will hereinafter appear such means together with the loopers are attached wholly to the frame cap 13. 55 Means for attaching this frame cap to the machine frame may vary. Heretofore in machines of similar construction said frame cap has been fitted to its receiving opening in the machine frame and secured by screws 60 at one edge only thereof. In the present 65

case, to more effectively eliminate vibration, I prefer to dispose positive securing devices, as screws 32, at opposite sides of the cap so that all moving parts sustained by the cap will be located intermediate the 70 points of attachment. Obviously the cap may be conveniently removed to permit inspection and adjustment of the looper mechanism.

Referring to Figs. 2 and 3, the supplemental supporting means for looper 21 will now be described. Attention may first be directed to the fact that the arm 30, has at its extreme ends a bearing against the inner surface of the frame cap 13, whereby 75 outward thrust thereagainst will be effectually resisted. Obviously this resistance is also similarly effective for the pivoted arm of looper carrier 22. Interposed between the oppositely extending arm of carrier 22 80 and the frame cap and between the central portion or mid arm 23 of said carrier and the frame cap are respectively the bearing blocks 33 and 34 fastened to said frame cap by suitable screws. Block 33 is recessed at 85 35 to accommodate arm 30. These blocks also resist outward thrust of the engaging parts, displacement of the carrier 22, therefore, in the direction indicated is effectively prevented by ample bearing contact at three 90 advantageously disposed points. Displacement of said carrier in the opposite direction to that just referred to is prevented by a guide bar 36, having an opposing surface which affords a bearing for the central portion or mid arm 23 of carrier 22 practically 95 throughout the length of said arm. 100

This opposing surface of guide bar 36 is spaced from the inner face of the frame cap by a spacing block 37, at one end of the bar, 105 and by an angularly extended foot 38 and the block 34, at the other end of the bar. Securing said bar to the frame cap are the screws 39 and 40, the former being countersunk in said frame cap, extended through the block 37 and threaded into the bar, while the latter is countersunk in the offset or angularly extended portion of the bar, extended through the block 34 and threaded into the frame cap. 110

From the foregoing it will be evident that the guiding or supporting surfaces for the loopers are ample in extent, disposed in a highly effective arrangement, and provided by parts well adapted for manufacture, adjustment, and maintenance. 115

There are shown in the drawings the usual tensions, guides and take-ups which being well understood need not be herein described in detail.

What I claim is:

1. In a sewing machine, looper mechanism including in combination, an oscillatory arm, a looper carried by and movable with respect to said arm, and a pair of cam 120

cylinders rotating in unison and having correlated cam grooves adapted to move said arm and looper in substantially parallel planes.

5. 2. In a sewing machine, looper mechanism including in combination, a frame cap supported by and removable from the machine frame, a pair of cams adjacent to said frame cap, an arm pivoted to the frame cap, a 10 looper movably carried by the arm and operable by the pair of cams; and supporting means attached to the frame cap and having opposed surfaces in contact with said looper.

3. In a sewing machine, looper mechanism 15 including in combination, a pair of cam cylinders, a pivotally mounted looper, a pivotally mounted arm, and a second looper movably carried by said arm, the first mentioned looper being operable by a cam groove in one 20 of the cam cylinders and the other looper being operable by correlated cam grooves in the cam cylinders.

4. In a sewing machine, looper mechanism 25 including in combination, a frame cap supported by and removable from the machine frame, a pair of cams adjacent to said frame cap, an arm pivoted to the frame cap, and a looper movably carried by the arm and operable by the pair of cams.

Copies of this patent may be obtained for five cents each, by addressing the "Commissioner of Patents,
Washington, D. C."

5. In a sewing machine, looper mechanism 30 including in combination, a frame cap, supported by and removable from the machine frame, a pair of cams adjacent to said frame cap, an arm pivoted to the frame cap, a looper movably carried by the arm and operable by the pair of cams, and means for securing the frame cap to the machine frame 35 said means being disposed on opposite sides of the looper mechanism supported by said cap.

6. In a sewing machine, looper mechanism including in combination, a frame cap supported by and removable from the machine frame, a pair of cams adjacent to said frame cap, a movable arm secured to the frame 45 cap, a looper movably carried by the arm and operable by the pair of cams, and means for securing the frame cap to the machine frame, said means being disposed on opposite sides of the looper mechanism supported 50 by said cap.

In testimony whereof I affix my signature in the presence of two witnesses.

JOSEPH M. MERROW.
